(57) CLAIM

The ornamental design for bottle packaging, as shown and described.

DESCRIPTION

FIG. 1 is a front perspective view of the bottle packing according to the present invention;

FIG. 2 is a front plan view of the bottle packing according to the present invention;

FIG. 3 is a rear plan view of the bottle packing according to the present invention;

FIG. 4 is a first side plan view of the bottle packing according to the present invention;

FIG. 5 is a second side plan view of the bottle packing according to the present invention;

FIG. 6 is a top plan view of the bottle packing according to the present invention; and,

FIG. 7 is a bottom plan view of the bottle packing according to the present invention.

The broken lines showing of a bottle in FIGS. 1 and 2 is for the purpose of illustrating environmental structure and form no part of the claimed design. The remaining broken lines shown in the drawings are for the purpose of illustrating portions of the bottle packaging and form no part of the claimed design.

The word mark "EMYLA" and the design mark shown in broken lines in FIGS. 1 and 2 form no part of the claimed design. The word and design mark are registered trademarks of EMYLA SPIRITS INC., under U.S. Trademark Registration Nos. 7,531,032, 7,237,520, and 7,226,035.

1 Claim, 4 Drawing Sheets
